CLOCK CASING

Monte L. Levin, New York, N.Y., assignor to General Time Corporation, Stamford, Conn., a corporation of Delaware

Filed Apr. 1, 1968, Ser. No. 11,227

Term of patent 14 years

U.S. Cl. D42—7
Int. Cl. D10—06

FIG. 1 is a front elevational view of a clock casing showing my new design;

FIG. 2 is a left side elevational view;

FIG. 3 is a top plan view; and

FIG. 4 is a rear elevational view wherein the essential features of my new design reside in the portions shown in full lines.

The broken line showings of a clock face and hands in FIGS. 1-3 are for illustrative purposes only.

I claim:

The ornamental design for a clock casing, substantially as shown and described.
